UNITED STATES PATENT OFFICE

149,355

DESIGN FOR A PLASTIC FABRIC

Fritz Hollstein, West New York, N. J.

Application November 7, 1947, Serial No. 142,389

Term of patent 3½ years

(Cl. D92—1)

To all whom it may concern:

Be it known that I, Fritz Hollstein, a citizen of the United States of America, residing in West New York, county of Hudson, and State of New Jersey, have invented a new, original, and ornamental Design for a Plastic Fabric, of which the following is a specification, reference being had to the accompanying drawing, forming part thereof.

The figure on the drawing is a plan view of a plastic fabric, showing my new design.

I claim:

The ornamental design for a plastic fabric, substantially as shown.

FRITZ HOLLSTEIN.
